[57] CLAIM

The ornamental design for a gymnasts hand grip, substantially as shown and described.

DESCRIPTION

FIG. 1 is a top perspective view of a gymnasts hand grip showing my new design in operative condition; FIG. 2 is a top perspective view in an extended condition;

FIG. 3 is a bottom plan view thereof;

FIG. 4 is an end elevational view, palm side down; and FIG. 5 is a top perspective view of a second embodiment of a gymnasts hand grip showing my new design.
